By James F. Gibbons Atty.

UNITED STATES PATENT OFFICE

GEORGE D. DOHERTY, OF MINNEAPOLIS, MINNESOTA, ASSIGNOR TO DOHERTY-BREHM COMPANY, OF MINNEAPOLIS, MINNESOTA, A CORPORATION OF DELAWARE

AIR HUMIDIFIER

Application filed March 12, 1930. Serial No. 435,052.

This invention relates to an air humidifier and heat radiator and has special reference to such an apparatus in which a forced circulation of air is effected over a heating section provided with an open trough containing a humidifying medium.

More particularly, this invention relates to a combined air humidifier and heat radiator comprising an apparatus having a plurality of heating sections with open troughs formed on the upper surfaces of each section, the assembled structure being disposed in a casing or housing having an air inlet and an air outlet at opposite ends thereof and a means for forcing a circulation of air therethrough and between the heating sections for the purpose of absorbing moisture from the humidifying medium in the troughs and of receiving a transmission of heat in order to maintain humidity in a room or other enclosure consistently with the proper degree of temperature of the room.

Further, since a fan or other like means is employed for forcing a circulation of air through the apparatus, one of the heating sections may be provided with an extension for supporting the fan in spaced relation to the floor in a manner to tend to deaden the vibration and thus to eliminate the usual accompanying noises. By supporting the fan in this manner, the whole mass or weight of the assembled structure is utilized for weighting down the vibrating mass of the fan proper and thus the vibrations tending to be set up by the fan during operation are substantially completely damped thus rendering operation of my combined humidifier and radiator noiseless since the fan is not in contact with the floor except through the base of the radiator and humidifier.

In explanation of the usefulness of my present invention the following comments are offered: It has been contended that the average person spends over eight percent of his or her time indoors during the winter months. The air in a home is heated, naturally, to a temperature which is comfortable to the body and, in most instances, the body does not feel comfortable until the air is heated to a comparatively high degree due

to the aridity of the air. It is the general belief that a temperature range of from 70 to 80 degrees is desirable and is usually maintained in homes yet it is a fact that the ideal temperature for good health is 64 degrees or at the most 68 degrees and under proper conditions of humidity this temperature is perfectly comfortable. It is concluded therefore that, in winter, most people live the greater part of the time under conditions which are not altogether desirable to good health.

Air normally contains from 40 to 60 percent of saturation with water. However, the relative humidity of air at zero is 100 percent, the air containing half a grain of water to a cubic foot of air. If this same air is heated to 70 degrees without the loss or gain of any moisture it would have a relative humidity of only 6.3 percent because a cubic foot of air at 70 degrees can contain about 8 grains of water. In order to supply this comparatively great amount of moisture to the air at the higher temperatures, it is contemplated to provide a forced circulation of air over a large exposed area of humidifying medium in direct contact with a heating section that serves to vaporize rapidly and in large volume the humidifying medium. The heating sections are spaced from one another and are severally provided over their upper surfaces with a trough for containing a humidifying medium. The assembled structure may replace the ordinary type of room radiator.

By reason of the peculiar disposition of the sections and the circulatory means, a maximum transmission of heat is obtained in the air and humidity may be maintained consistently at the proper degree.

One of the objects of this invention is to provide an apparatus of the character above noted in which a forced circulation of air is provided between spaced heating sections in which the humidifying medium is exposed to the air over substantially the entire upper surface of the section.

Another object of this invention is to provide an apparatus as characterized above in which the air to be humidified is circulated

by forced means between heating sections disposed in a casing, the air being admitted and exhausted through opposite ends of the casing.

6 A still further object of this invention is to provide an apparatus of the character indicated above in which the fan motor or other forced-feed means is substantially completely damped by the weight of the assembled structure to eliminate vibration and 10 the usual accompanying noises.

Other objects and advantages will herein-after be more particularly pointed out and for a more complete understanding of the 15 characteristic features of this invention reference may now be had to the following description when taken together with the accompanying drawing, in which latter:

Figure 1 is a top plan view of the apparatus embodying the features of this invention with the casing thereof in section;

Fig. 2 is a front elevational view of the apparatus shown in Figure 1 with the casing thereof being shown in section;

25 Fig. 3 is a top plan view of the lower tray for supporting the heating sections of the apparatus of this invention; and

Fig. 4 is a central vertical sectional view taken on the line 4—4 of Fig. 2.

30 Referring now more particularly to the drawing, the specific embodiment of this invention comprises a supporting tray 10 having a plurality of superposed horizontally extending heating sections 11 mounted thereon. The supporting tray 10 comprises a 35 somewhat shallow rectangular trough supported at the four corners thereof by legs 12. The tray is preferably provided with a central elongated longitudinally extending 40 opening 13 to permit the passage of air therethrough, as will hereinafter be more particularly pointed out. It is, of course, to be understood that these openings may be varied in number and size and that the tray 45 may not be provided with an opening, as desired, depending upon the size of the unit and the like.

Each of the heating sections 11, in ordinary domestic use, comprises preferably a 50 plurality of longitudinally extending hollow heating units 14 which are connected together at their outer ends to form a circuitous passageway for the circulation of a heating medium. It is, of course, to be understood 55 that each heating section may comprise a single heating unit as well as any number of heating units, the drawing showing a double unit merely for the purpose of illustration. Further, these units may be arranged 60 to have a larger number of heating units in one section than in the adjacent section or sections. The sections are preferably cast with a peripheral flange 15 extending around the outer edges of the unit and 65 across the ends thereof to form a continu-

ous exposed recessed portion or trough for containing a humidifying medium. The two units forming the heating section provide an open space therebetween to form a central passageway for air in communication with the passageway or opening 13 of the tray 10. By reason of these passageways, an efficient transmission of heat to the air is obtained, the lower portion of each of the units being rounded and converging 75 slightly upwardly to direct the natural circulation of air around each unit of the heating section.

The open troughs formed on the upper faces of the heating sections by means of the peripheral flange 15 are adapted to hold a humidifying medium that is imparted to the heated air as it circulates around and longitudinally through the spaces between the heating sections. Means are provided between the superposed sections for connecting the troughs of the adjacent sections to one another comprising a conduit 16 which is preferably formed integrally with the casting and extends vertically from a point just 80 above the upper surface of the heating section, which latter forms the bottom surface of the trough, to a point adjacent the trough of the heating section next below.

85 These conduits 16 are arranged in a staggered vertical direction or in any other suitable manner other than in alignment with each other, which latter arrangement, it is submitted, would permit the humidifying medium to fall from the upper sections directly to the lower tray. This, of course, would be highly undesirable, as will herein-after be fully understood, the upper trough being supplied with the humidifying medium and it, in turn, supplying the other troughs therewith. It has been stated that the conduit extends from a point a slight distance above the base of the trough to a point adjacent the trough next below. In 90 this manner, a lip 17 is provided for maintaining a minimum level of humidifying medium in each trough. Therefore, each of the several troughs forming the assembled structure will always contain a minimum supply of humidifying medium.

115 The lower rounded portion of each unit of each heating section is provided with a drip-edge 18 whereby, should one of the conduits 16 become clogged with foreign matter, the humidifying medium would overflow the peripheral flange 15 and drip into the trough next below. This drip-edge 18 would, of course, direct the overflow into the trough next below thereby preventing the humidifying medium from dropping into any of the air passageways and from thence to the floor.

120 Each of the heating sections is provided with a boss 19 on each side and at each end thereof for supporting and connecting the adjacent heating sections together. These 125 130

bosses further provide for a circulation of the heating medium from one heating section to the other by reason of the nipple connections 19a therebetween. The uppermost 5 heating section is provided with the usual plug to prevent the escape of the heating medium. The lowermost heating section is connected to the supporting tray 10 in the same manner as each section is connected together, the tray being provided with a boss 20 on the face surfaces and at opposite ends thereof, the bosses, in turn, communicating with end bosses 21 which are connected to the inlet and outlet conduits 22 and 23, respectively. The circulation of the heating medium, therefore, is from the inlet 22 through the passageway formed between the bosses 21 and 20 at one end into the circuitous passageways of the heating sections 15 midifying medium to the air forced in contact therewith provides an efficient means for the transfer of moisture into the air. By reason of providing this maximum amount of humidifying medium and the forced contact therewith of air to be heated and humidified, it is possible to maintain humidity in a room or other enclosure consistently at the proper degree.

10. While but a single embodiment of this invention is herein shown and described, it is to be understood that various modifications thereof may be apparent to those skilled in the art without departing from the spirit and 15 scope of this invention, and therefore, the same is to be limited only by the scope of the prior art and the appended claims.

I claim:

1. An apparatus of the character described, 20 comprising a plurality of spaced and superposed heating sections connected to one another for circulating a heating medium therethrough, said sections, when assembled together, constituting a rigid mass of substantial weight, means on said sections for containing a humidifying medium for imparting humidity to the heated air, and an electric fan motor wholly mounted on said assembled structure for forcing a circulation of air longitudinally between said sections and in contact with said humidifying medium, the vibrations of said fan motor being damped effectively by the mass of said assembled structure.

35. 2. An apparatus of the character described, comprising a plurality of spaced and superposed heating sections connected to one another for circulating a heating medium therethrough, said sections, when assembled together, constituting a rigid mass of substantial weight an open trough on at least one of said sections containing a humidifying medium for imparting humidity to the heated air, and an electric fan motor wholly mounted 40 on said assembled structure for forcing a circulation of air longitudinally over said open trough and in contact with said humidifying medium, the vibrations of said fan motor being damped effectively by the mass of said 45 assembled structure.

50. 3. An apparatus of the character described, comprising a plurality of spaced and superposed heating sections connected to one another for circulating a heating medium therethrough, said sections when assembled together, constituting a rigid mass of substantial weight, a peripheral flange bounding the edges of at least one of said sections to provide an open trough containing a humidifying medium for imparting humidity to the heated air, and an electric fan motor wholly supported on said assembled structure for forcing a circulation of air longitudinally over said humidifying medium and in contact with 55 said humidifying medium, the vibrations of

said fan motor being damped effectively by the mass of said assembled structure.

4. An apparatus of the character described, comprising a plurality of spaced and superposed heating sections connected to one another for circulating a heating medium therethrough, said sections, when assembled together, constituting a rigid mass of substantial weight, means on each section for containing a humidifying medium for imparting humidity to the heated air, an electric fan motor wholly supported on said assembled structure inducing a flow of air longitudinally between said sections and in contact with said humidifying medium to evaporate the latter, and a casing sound insulated from said structure and said electric fan motor and being disposed about said heating sections and said circulating means.

5. An apparatus of the character described, 85 comprising a plurality of spaced and superposed heating sections connected to one another for circulating a heating medium therethrough, said sections, when assembled together, constituting a rigid mass of substantial weight, means on at least one section containing a humidifying medium for imparting humidity to the heated air, an electric fan motor wholly supported on said assembled structure for creating a circulation of air longitudinally between said sections and in contact with said humidifying medium, the vibrations of said fan motor being damped effectively by the mass of said assembled structure, and a casing for enclosing said heating 90 sections and said circulation means, said casing having an air inlet at one end thereof adjacent said circulating means and an air outlet at the other end thereof and being sound insulated from said assembled structure and 95 said fan motor.

6. An apparatus of the character described, comprising a plurality of spaced and superposed sections connected to one another for circulating a heating medium therethrough, 100 an extension on one of said sections for supporting a fan motor, means on at least one section for containing a humidifying medium for imparting humidity to the air forced between said sections by said fan motor, and a resilient 105 material between said motor and said extension for deadening the vibration and accompanying noises therefrom.

7. An apparatus of the character described, 110 comprising a plurality of spaced and superposed sections connected to one another for circulating a heating medium therethrough, an extension on one of said sections for supporting a fan motor, means on at least one section for containing a humidifying medium 115 for imparting humidity to the air forced between said sections by said fan motor, said extension having a pocket therein, and a cushioning material resting loosely against the walls of said pocket, said motor resting 120 125 130

freely on said cushioning material for deadening the vibration and accompanying noises therefrom.

8. An apparatus of the character described, comprising a plurality of spaced and superposed castings connected to one another for circulating a heating medium therethrough, an extension on one of said castings for supporting a fan motor, means on at least one casting for containing a humidifying medium for imparting humidity to the air forced between said castings by said fan motor, said extension being formed integrally with said casting and having a pocket therein, and a cushioning material resting loosely against the walls of said pocket, said motor resting freely on said cushioning material for deadening the vibrations and accompanying noises therefrom.

20 9. An apparatus of the character described, comprising a plurality of spaced and superposed heating sections connected to one another for circulating a heating medium therethrough, at least some of said sections comprising longitudinally extending hollow castings having peripheral flanges on the upper surface thereof to provide troughs for containing a humidifying medium for imparting humidity to the heated air forced between 25 said sections, said castings with the troughs having drip edges on the underneath walls thereof, that are longitudinal of the castings, said drip edge on the upper casting being above the trough of the lower casting for 30 directing the overflow into said lower trough, and a tray for supporting said heating sections and for receiving the overflow of said humidifying medium directed thereto by said drip edges.

40 10. A combined heat radiator and air humidifier apparatus comprising a plurality of separate and spaced heating sections that are rigidly connected to one another for circulating a heating medium therethrough, at 45 least one of said sections having a trough for containing a humidifying medium that extends substantially completely over the upper surface thereof, a lateral extension secured to one of said sections and spaced from the floor upon which said apparatus is disposed, an electrically operated fan supported upon said lateral extension that serves to circulate air between said sections and over said trough, a resilient vibration dampening 50 material interposed between said fan and said lateral extension, said rigidly connected sections serving as a weight to dampen the vibrations developed by said fan, and a casting surrounding the fan and said sections 55 which is free from mechanical contact therewith.

60 11. In a combined heat radiator an air humidifier apparatus comprising a plurality of superposed and spaced heating sections, at 65 least one heating section constituting a lon-

gitudinally disposed chamber for a heating medium and having an exposed trough integrally formed therewith that extends substantially completely over the upper surface thereof for containing a humidifying medium, a lateral extension secured to one of said sections and spaced from the floor upon which said apparatus is disposed, and an electrically operated fan supported on said lateral extension and sound insulated therefrom and adapted to force air longitudinally between said built up sections and over said trough whereby humidity may be imparted to said air, said sections constituting a weight or mass for dampening vibrations developed by said fan.

70 12. A combined air humidifier and heat radiator comprising a plurality of spaced and superposed heating sections connected to one another for circulating a heating medium therethrough, at least two sections being provided on their upper surfaces with exposed troughs for containing a humidifying medium, the upper section having an overflow, and means for maintaining in said trough a certain predetermined level of the humidifying medium therein and the lower trough being provided with an upstanding lug disposed underneath the overflow of said upper trough to break the fall of the humidifying medium flowing therethrough from 75 said upper trough.

80 13. A combined air humidifier and heat radiator comprising a plurality of spaced heating sections superposed directly upon one another and being connected to one another for circulating a heating medium therethrough, at least two heating sections comprising longitudinally extending hollow castings for containing the heating medium and said castings having peripheral flanges on the upper surface thereof to provide open troughs for containing a humidifying medium for imparting humidity to the heated air, the upper section having a drip edge 85 formed on the under wall thereof whereby the humidifying medium dripping from said edge is directed into the trough of the lower casting, and means in the upper trough for maintaining therein a predetermined level 90 of the humidifying medium.

95 In witness whereof, I have hereunto subscribed my name.

GEORGE D. DOHERTY.
